UNITED STATES PATENT OFFICE

98,746

DESIGN FOR A CARPET

Michael S. Miller, Thompsonville, Conn.

Application October 16, 1935, Serial No. 59,086

Term of patent 3½ years

To all whom it may concern:

Be it known that I, Michael S. Miller, a citizen of the United States of America, residing in Thompsonville, county of Hartford, and State of Connecticut, have invented a new, original, and ornamental Design for a Carpet, of which the following is a specification, reference being had to the accompanying drawing, forming part thereof, wherein,

The figure is a plan view of a piece of a carpet showing my new design.

The carpet forming the subject matter of this

application is of a single color, the lighter portions of the drawing representing relatively lighter tones while the darker portions of the drawing represent relatively darker tones, the nap being in practically a single plane surface. The figure shows a single unit between the lines A—A and B—B, which unit is repeated indefinitely resulting in a herringbone appearance.

I claim:

The ornamental design for a carpet substantially as shown and described.

MICHAEL S. MILLER.
